UNITED STATES PATENT OFFICE.

TEILE H. MÜLLER, OF NEW YORK, ASSIGNOR TO SAMUEL S. HEPWORTH,
OF YONKERS, N. Y.

CENTRIFUGAL MACHINE.

SPECIFICATION forming part of Letters Patent No. 298,395, dated May 13, 1884.

Application filed December 31, 1883. (No model.)

To all whom it may concern:

Be it known that I, TEILE H. MÜLLER, a resident of New York city, in the county and State of New York, have invented an Improved 5 Centrifugal Machine for Separating Liquids from Solids, of which the following is a full, clear, and exact description, reference being made to the accompanying drawings, in which—

10 Figure 1 is a vertical central section of my improved centrifugal machine. Fig. 2 is a side view of the top portion of said machine; Fig. 3, a top view, partly in section, of said top portion; Fig. 4, a side view, partly in section, 15 of the suspension-socket of the machine; Fig. 5, a top view of said suspension-socket; Fig. 6, a side view of the supporting-socket used in the upper portion of the machine; Fig. 7, a partial top view of said socket; Fig. 8, a top 20 view, partly in section, of the brake-ring used on the machine, and of its connections. Fig. 9 is an enlarged vertical central section of the upper portion of the machine; Fig. 10, an enlarged vertical central section of the lower 25 portion of the machine; and Fig. 11 is a horizontal section on the plane of the line *c c*, Fig. 10, but drawn on the same scale as Fig. 1.

The object of this invention is to furnish a 30 centrifugal machine which shall be able to work all kinds of sugars and other substances, and yet have all the different parts light and easy of repair, without communicating the vibrations of the frame-work from which the machine is suspended.

35 The machine to which these improvements pertain belongs to that class of centrifugals which are directly suspended from the upper portions of their spindles, and which have no support at the lower parts of the spindles; but 40 the machine invented by me differs from those heretofore in use, in that the spindle is held in a central position by bottom bearings, which affect its position laterally, but do not support it.

45 The invention consists in a novel construction of oscillating suspension-head and stationary suspension-socket, and in the combination of these parts with each other and with the lateral bottom bearing.

50 It also consists in other details of combina-

tion and construction that are hereinafter more fully specified.

In the drawings, the letter A represents a spindle of the centrifugal machine, which spindle at its lower portion carries the basket 55 B, that is fastened to it in the usual or suitable manner. The upper end of this spindle A has, by preference, screwed into it a separate short spindle, C, for the purpose of employing in this upper part a superior quality 60 of steel, and also to avoid crystallizations, which may occur in larger forgings and prove fatal if they should creep into the upper part of the spindle proper.

The uppermost part of the spindle-top Chas 65 attached to it, preferably by a screw-thread, a nut, *a*. This nut may be further fastened by a traversing pin, *b*, so as to avoid all danger of its working loose. The lower face of the nut *a* is in contact with the upper one of 70 a series of washers, *d*, which rest on an annular plate, *e*, that is firmly screwed into or otherwise secured in the tubular piece D, which I term the "head" of the suspension apparatus. This head has at its lower end a nearly 75 semi-spherical enlargement, *f*, which rests in a nearly semi-spherical socket, *g*, that is formed in the lower part of a tube, E, which surrounds the tube D, as is more clearly shown in Fig. 9. The upper end of the tube E has 80 an outwardly-extending flange, *h*, which by bolts *i* connects with the suspension-socket F. This suspension-socket is shown in plan view in Fig. 5, and in side view, partly in section, in Fig. 4, and is provided, as these drawings show, with four (more or less) vertical tubular extensions, *j*, that pass through openings in the flange *k* of the head D, said openings in said flange *k* being so large that during any possible vibrations of the head D the 85 body of the latter will not come in contact with the tubular extensions *j* of the suspension-socket F. The suspension-socket itself is secured by strong bolts to the upper framing, G, of the building in which the machine 90 is erected.

The bolts showing the connection between the suspension-socket F and the beam G are indicated by dotted lines in the upper part of Fig. 1, and by full lines at *m* in Fig. 2. Thus 95 100

the tube E, having the female bearing part g, is rigidly suspended from the suspension-head F, and by it is supported through the intervention of the head D, having the enlargement f, and the bearing-plate e, the spindle A itself. The inner face of the head D is, by preference, lined with a brass tubing, n, in or with which the shaft A revolves without carrying around with it the tube or head D. Any oscillation of the shaft A will be taken up by the ball-and-socket joint f g.

From a suitably-arranged oil-cup on the suspension beam or bracket, G, oil is fed into the central upper part of the head D, which oil will surround the washers d and ascend around them and around the prolongation C of the spindle A until it rises to the level of a hole in the side or top of a tube, o, that projects vertically upward from the annular plate e, as is clearly shown in Fig. 9. A passage leads through the annular plate e in alignment with the bore of the tube o, so that the oil which flows from above into the tube o will pass through said tube and through said passage into the space below the plate e, lubricating the sides of the spindle A where they turn in or with the bushing n, and finally this oil will be caught in the inside of the pulley H, whence it can be removed by suitable means. Thus by means of said tube o, in the position stated, the oil will be prevented from rising in the upper part of the head D above the level which is prescribed for it by the height of the aperture in the upper part of the tube o. The pulley H is rigidly mounted at its lower portion upon the shaft or spindle A, being secured thereto by clamping-nuts or in any other suitable manner. The lower part of this pulley is made of inverted, truncated, conical form, as shown at p in Fig. 9, while the upper part is made cylindrical, as shown at q in the same figure. The belt for revolving the spindle A and its appendages is placed around the cylindrical portion q of the pulley H. The conical portion p of said pulley is embraced by a tapering hollow brake, I, of corresponding form, which hollow brake has its inner face lined with blocks r of wood or other frictional substance. The form of the brake I is that of a tapering dish with open bottom and top. Figs. 2 and 8 show how this brake is connected to the other parts of the machine, namely: It is pivoted by a horizontal pivot, s, to a sleeve, t, that is held on a bolt, u, which is fastened in a proper socket on the flange k of the suspension-head D. Fig. 3 shows a top view, partly in section, of this suspension-head D.

Diametrically opposite to the bolt u the head D carries another vertical bolt, v, which is embraced by a hollow extension, w, of the brake I. The said hollow extension has a cam-like or inclined lower edge, below which there is swiveled, on the bolt v, a lever, J, having a cam-like or inclined portion on its upper face. By swinging this lever J around the bolt v, it will serve to either raise or lower the free end of

the pivoted hollow brake I. When the lever is turned to lift the brake, it will cause the latter to bear tightly against the outer conical face of the portion p of the pulley H. The resistance which is produced by this contact on the revolving spindle is not only lateral but also vertical—that is to say, the spindle, together with its pulley H and suspension-head D, is bodily lifted to a slight extent whenever the brake is applied, and thus its rotation will be speedily stopped. The lifting of the spindle by the application of the brake has for its effect, moreover, to release the pressure on the washers d, and to allow the oil which is contained in the upper part of the suspension-head D to enter between the washers and to keep their surfaces properly lubricated. When I say "washers" in this connection, I mean any arrangement of plate or plates that is interposed between the nut or enlargement a and the supporting-plate e, for the purpose of reducing friction. Such plate or plates may have the form indicated in the sectional view, Fig. 9, or other analogous form, or may be provided with anti-frictional rollers or balls, if desired. The braking effect produced by lifting the brake I, so far as the rotary motion of the spindle A and its appendages is concerned, is to transfer the resistance by the head D to the tubular projections j, that pass through the head, and these projections being stationary and being secured to the framing or building in which the machine is suspended, the machine is quickly stopped.

We now come to the lower part of the machine. Here the spindle A carries the basket B, which, as already stated, is of suitable construction. Below the basket the spindle is prolonged to receive the lower bearing, which bearing consists of an upper portion, a², brass bushing b², and lower portion, d², as is more clearly indicated in Fig. 10. The upper part, a², of the bearing forms a hollow guard in its highest portion, which guard surrounds the spindle and prevents the oil from splashing over. In the middle this upper part, a², of the bearing has a cylindrical projection which reaches downward and rests on the bushing b², said bushing being supported on a shoulder or head, e², that is formed at the lower end of the spindle A. The lower portion, d², of the bearing surrounds the bushing b², and is in its upper part embraced by the portion a², as shown, and reaches to above the level of the oil that flows through an opening, i², from a² into d². Vertical bolts f², which extend through flanges of the portions a² and d², serve to connect with the latter a series of radiating horizontal bolts or braces, L, of which six are shown in Fig. 11—that is to say, the inner ends of these radiating horizontal bolts or braces L are coupled to the lower bearing by the short vertical bolts f². The headed outer ends of the horizontal bolts or braces L extend through a vertical flange or projection, g², of the outer gutter or casing, M, which is indi-

cated in Fig. 1, and are surrounded by rubber cushions or analogous springs h^2 on the outer side of said flange g^2 , and inside of the heads of said braces.

5 The bearing for the lower part of the spindle is applied as follows: The upper portion, a^2 , is first slipped over the spindle from below. The bushing b^2 , made in halves, is then placed on the neck of the spindle over the head e^2 , 10 and then the oil-chamber or lower portion, d^2 , is slipped on, and then the two parts a^2 and d^2 are united to one another, and likewise to the horizontal bolts L by the vertical bolts f^2 . It will be readily seen that the horizontal bolts 15 or braces L , in connection with their cushions h^2 , will serve to keep the lower bearing, a^2 d^2 , duly centered, yielding sufficiently, however, to the gyrations of the spindle to prevent any undue strain upon the suspension mechanism, 20 and nevertheless always assisting to prevent undue gyrations.

I claim—

1. The combination of the spindle A , having the upper enlargement, a , with the washers d , supporting-plate e , tubular head D , ball-and-socket joint f g , tube E , bolts i , and suspension-socket F , having tubular extensions j , that pass through apertures in the flange k of the head D , substantially as herein shown 25 and described.

2. The combination of the spindle A and its prolongation C and upper enlargement, a , with the washers d , tubular head D , and means, substantially as described, for supporting said head, and with the plate e and oil-tube o , that 30 extends upward from said plate e , said plate e having a passage in alignment with the bore of the tube o , substantially as and for the purpose herein shown and described.

3. The combination of the suspended spindle A , and means, substantially as described, for holding it suspended, with the pulley H , having conical portion p , and with the conical brake I , horizontal pivot s of said brake, and means, substantially as described, for swinging 45 said brake on said pivot, as set forth.

4. The combination of the suspension-socket F , having tubular extensions j , with the tube E , suspension-head D , having flange k , through which the tubes j pass, spindle A , enlargement 50 a , washers d , supporting-plate e , pulley H , and brake I , all arranged so that when the brake is applied the spindle will be slightly lifted and pressure on the washers relieved, as set forth.

5. The combination of the suspended spindle A with the guard a^2 , split sleeve b^2 , chamber d^2 , horizontal braces L , fixed flange or projection g^2 , and cushions h^2 , substantially as and for the purpose herein shown and described. 60

6. The combination of the upright spindle A and means, substantially as described, for suspending it at its upper end, with a bottom bearing and centering braces and cushions L h^2 , substantially as herein shown and described. 65

7. The combination of the split sleeve b^2 and oil-chamber d^2 , having a vertical prolongation to above the level of the oil, and outer flange for bolts f^2 , with a guard, a^2 , resting on the inner bushing, b^2 , and reaching over said 70 projection of the oil-chamber, and forming upper flange for attaching tension-bolts L , as set forth.

TEILE H. MÜLLER.
